UNITED STATES PATENT OFFICE

FRANK L. LINDSTROM, OF BRIDGEPORT, CONNECTICUT

TOY SCROLL SAW

Application filed April 7, 1932. Serial No. 603,730.

My invention relates to new and useful improvements in toy scroll saws such as are adapted to be hand operated, and obviously adapted for light sawing.

5 The object of the invention is to design a simple and practical mechanical toy of this character which can be inexpensively manufactured and placed upon the market to sell in volume, in small sizes, for twenty-five cents or less.

10 A further object of the invention is to so design the machine that its four more-important parts may be inexpensively stamped up from sheet metal and assembled with the wire saw frame and cast metal cam wheel in a manner which will avoid expensive drilling, tapping and other machine work, which have heretofore been necessary in the production of a scroll saw of this general character.

15 With these and other objects in view, the invention resides and consists in the construction and novel combination and arrangement of parts hereinafter more fully described, illustrated in the accompanying drawing, and pointed out in the claims hereto appended, it being understood that various changes in the form, proportion, size, and minor details of construction within the scope of the claims 20 may be resorted to without departure from the spirit, or sacrificing any of the advantages of the invention.

25 Similar characters of reference denote like or corresponding parts throughout the several figures of the accompanying drawing forming a part of this specification and upon which

30 Fig. 1 shows a side elevation of my improved toy scroll saw complete;

35 Fig. 2 illustrates the opposite side view of the saw shown in Fig. 1;

40 Fig. 3 illustrates a front elevation of the saw;

45 Fig. 4 is a detailed vertical sectional view through the cam wheel and the fixed spindle support for the same; and

50 Fig. 5 shows a detached top edge view of the saw-frame carriage, better to illustrate one of the two guide slots therein.

55 Referring in detail to the characters of ref-

erence marked upon the drawing, 10 represents the base of the machine which, as will be observed, is adapted to be blanked and stamped up from sheet metal, at which time one or more elongated openings 11 may be formed in its central portion to receive the lower end portion of the vertically disposed sheet metal pedestal 12 upon which the saw table 13 is mounted, said mounting being preferably accomplished in the same manner as the connection at the bottom end of the pedestal by means of providing one or more elongated slots in the table to receive projected end portions of the column. This column is preferably provided with a rib 14 upon each of its vertical edge portions.

55 The saw-carriage 15 is also formed of sheet metal that is blanked up, see Figs. 3 and 5, to form a main body portion in which a transverse cam slot 16 is formed, and having upper and lower inwardly disposed flanges 17 and 18, each of which is provided with a slot 19, see Fig. 5, to receive the ribbed column 12 heretofore mentioned. From the foregoing, it will be seen that the carriage is free to be reciprocated vertically upon the column and along with it the saw frame 20 which is secured to the upper flange 17 by means of screws 21 passing through holes in the lower end portion of the saw frame, and engaging tapped holes 22 in the upper flange.

60 The saw proper, designated as 23, has its opposite end portions secured in the slotted ends 24 and 25 of the saw frame and is positioned to freely operate in a central hole 26 of the table. The carriage 15, its saw frame and saw, are reciprocated on the column vertically by means of an operating wheel 27 that is mounted upon a shouldered screw stud 28 that is secured to the column through a bushing 29 and a nut 30, the latter being mounted upon a reduced threaded end of the screw in a way to secure the same to the column.

65 The wheel is provided upon its inner side with an eccentric cam 31 that is positioned to turn in the before mentioned cam slot 16 in a manner to raise and lower its saw frame and saw, once with each rotation of the wheel. The wheel is further provided with an operating handle 32 by means of which it is freely

rotated on the stud 28 in a way to turn its cam within the slot and move the parts in a manner to move the saw up and down through the hole in the table.

5 The base of the saw may be provided with one or more screw holes 33 to permit it to be clamped to a table and whereby an operator may more easily perform sawing operations by rotating the wheel with one hand 10 and guiding the stock to be sawed, with respect to the saw, with the other hand.

Having thus described my invention, what I claim and desire to secure by Letters Patent is:

15 1. In a scroll saw of the class described, a base plate, a relatively wide sheet metal column secured to the base plate, a table secured to the top end of the column, a stud secured to the column, a cam wheel rotatably mounted 20 on the stud, a sheet metal carriage disposed crosswise of the column and of a width slightly greater than that of the width of the column and provided with a transverse slot engaged by the cam to vertically reciprocate 25 the carriage, and having inward edges with oppositely positioned elongated guide slots to engage the column and guide the carriage in its vertical reciprocatory movements with respect to the column, and a saw-frame and saw 30 mounted on the carriage to be reciprocated thereby.

2. A scroll saw of the class described, comprising a base, a relatively wide sheet metal column secured to the base and provided with 35 parallel ribs along its vertical edges, a table secured to the top end of the column, a stud secured to the column, a cam wheel rotatably mounted on the stud, a sheet metal plate forming a carriage provided with a transverse slot 40 engaged by the cam to vertically reciprocate the carriage, said plate carriage having its upper and lower edges deflected inwardly and provided with guide slots to receive the column to guide the carriage on and in spaced 45 relation to the column, and a saw-frame and saw mounted on the carriage.

Signed at Bridgeport in the county of Fairfield and State of Connecticut this 6th day of April A. D. 1932.

50 FRANK L. LINDSTROM.
